UNITED STATES PATENT OFFICE.

FRANCIS DWIGHT STANDERS, OF JOHNSTON, IOWA.

DESIGN FOR A WHEELED TOY.

Application filed March 19, 1928. Serial No. 25,917. Term of patent 3½ years.

To all whom it may concern:

Be it known that I, FRANCIS D. STANDERS, a citizen of the United States, and resident of Johnston, Polk County, Iowa, have invented a new, original, and ornamental Design for a Wheeled Toy, of which the following is a specification, reference being made to the ac-

companying drawing, forming part thereof.

The figure is a perspective view of a wheeled toy showing my new design.

I claim:

The ornamental design for a wheeled toy, as shown.

FRANCIS DWIGHT STANDERS.
